UNITED STATES PATENT OFFICE.

CHARLES J. JONES, OF CHEYENNE, WYOMING.

WEATHER-STRIP.

1,352,275.

Specification of Letters Patent. Patented Sept. 7, 1920.

Application filed July 29, 1919. Serial No. 313,979.

To all whom it may concern:

Be it known that I, CHARLES J. JONES, a citizen of the United States, and a resident of Cheyenne, in the county of Laramie and 5 State of Wyoming, have invented a new and Improved Weather-Strip, of which the following is a full, clear, and exact description.

This invention relates to improvements 10 in weather strips, an object of the invention being to provide improved weather strips for the meeting edges of window sash and frame, the meeting rails of the sash or the meeting faces of the door frame and door, 15 which serve to keep out the air and which form a snug juncture of the parts to prevent rattling.

A further object is to provide weather strips of the character stated which can 20 be manufactured and sold at a reasonably low price, which can be readily attached by anyone of average intelligence, not requiring any skilled labor, and which will most efficiently perform the functions for which 25 they are intended.

With these and other objects in view the invention consists in certain novel features of construction, and combinations and arrangements of parts, as will be more fully 30 hereinafter described and pointed out in the claims.

In the accompanying drawings—

Figure 1 is a view partly in elevation and partly in vertical section illustrating my im- 35 provements;

Fig. 2 is an enlarged view in transverse section on the line 2—2 of Fig. 1;

Fig. 3 is a similar view in section on the line 3—3 of Fig. 1;

Fig. 4 is a similar view in section on the line 4—4 of Fig. 1;

Fig. 5 is a fragmentary view in elevation partly broken away illustrating my improvements in connection with a door; and

Fig. 6 is a view in transverse section on the line 6—6 of Fig. 5.

Referring particularly to Figs. 1, 2, 3 and 4, 1 represents a window frame and 2 and 3 the upper and lower sashes respectively, 50 fitting in the groove 7 of the frame, as is customary in the art. In the groove 7 of the vertical members of the frame and between the same and the side rails 4 of the upper and lower sashes, weather strip mem- 55 bers 5 and 6 respectively are located, as shown most clearly in Fig. 3. The member

5 is secured to the frame, fits the groove 7 therein, is relatively flat throughout its width, and at its edges is provided with inwardly turned flanges 8.

The member 6, which is secured to the sash, also constitutes a strip having its intermediate portion bowed, as shown at 10, and its edges mounted to slide in the inwardly turned flanges 8 of member 5. The bowed portion of strip 6 is secured by means 65 of screws 9 to the rail of the sash, and the screws 9 are employed for attaching the member 5 to the frame.

I have used the reference numeral 9 to 70 indicate the screws for attaching all of the strips and would have it understood that I might use any form of securing device other than screws if desired.

In the groove 7 of the frame 1 at the top 75 and bottom thereof between the upper sash rail of sash 2 and the lower sash rail of sash 3, I locate similar weather strips, as shown most clearly in Fig. 2. These weather strips are given reference numerals 80 11 and 12 respectively, and they are both made with outwardly bowed intermediate portions contacting with each other, the edges of the strips being secured to the sash and frame respectively by means of 85 screws 9.

The meeting rails 24 of the sashes are provided with weather strip members 16 and 17, shown most clearly in Fig. 4. The member 16 is secured at its lower portion to 90 the meeting rail 24 of lower sash 3 by means of screws 9 and at its upper portion is offset laterally, as shown at 18, to enter a lip 19 on the weather strip member 17, which is secured by screws 9 to the meeting rail 95 of the upper sash. This lip 19 first projects upwardly and then downwardly, as shown in Fig. 4, so that it houses the upper end of the member 16 serving to exclude the air and also to hold the meeting rails tightly 100 together.

In Figs. 5 and 6, I have illustrated an improved form of weather strip adapted for use in connection with a door. In these figures, 20 represents the door frame, 21 the door and 22 the weather strip, which is secured to the frame 20 and has an outwardly bowed portion 23 against which the door contacts when in closed position.

While, of course, my invention is not limited to any particular material, I preferably 110 employ relatively thin metal which has suf-

ficient elasticity to insure a binding action without disfiguring or marring the shape of the strips, and it is understood that there is sufficient contact to provide a tight joint which excludes the air and prevents rattling.

Various slight changes may be made in the general form and arrangement of parts described without departing from the invention, and hence I do not limit myself to the precise details set forth but consider myself at liberty to make such changes and alterations as fairly fall within the spirit and scope of the appended claims.

15 **I claim:**

1. As a new article of manufacture, a weather strip comprising two members, one of said members adapted to be secured to a window frame and the other of said members to a window sash, one of said members having relatively flat longitudinal edges, and a transversely bowed intermediate portion, whereby a spring pressure is had of one strip against the other when in position 25 between the sash and the frame.

2. A weather strip, comprising two members, one member relatively flat and having inwardly turned flanges at its longitudinal edges, the other member having relatively flat edge portions located under the flanges, 30 and said last-mentioned member bowed transversely and having securing means at the center of its bowed portions.

3. The combination with a window frame and a sash, said frame having grooves to 35 receive the sash therein, of weather strips located in the grooves between the edges of the sash and the frame, said weather strips comprising two members, one member relatively flat and secured to the frame, inwardly turned flanges at the edges of said member, the other of said members having relatively flat edges mounted to slide under the flanges of the first-mentioned member and having a transversely bowed intermediate portion, and securing devices projected through the center of said bowed portion and secured in the sash.

CHARLES J. JONES.
